CLAIM

(22) **Filed:** **Feb. 21, 2018**

We claim the ornamental design for a display screen or portion thereof with transitional graphical user interface, as shown and described.

Foreign Application Priority Data**DESCRIPTION**

Aug. 30, 2017 (KR) 30-2017-0040526

FIG. 1 is a first image of a display screen or portion thereof with transitional graphical user interface showing our new design;

(51) **LOC (12) Cl.** **14-04**

FIG. 2 is a second image thereof;

(52) **U.S. Cl.**

FIG. 3 is a third image thereof;

USPC **D14/485**

FIG. 4 is a fourth image thereof;

(58) Field of Classification Search

FIG. 5 is a fifth image thereof;

USPC D14/485-489
CPC H04L 12/581; H04L 12/1813; G06F 19/3406; G06F 17/30873; G06F 3/0481; A61B 5/02; H04N 21/478; G06Q 10/10; G06Q 10/107

FIG. 6 is a sixth image thereof; and,

See application file for complete search history.

FIG. 7 is a seventh image thereof.

References Cited

The outer perimeter shown in a pair of dashed broken lines in the drawings represents a display screen or portion thereof and forms no part of the claimed design. The remaining dashed broken lines in the drawings illustrate portions of the transitional graphical user interface that form no part of the claimed design.

U.S. PATENT DOCUMENTS

The appearance of the transitional image sequentially transitions between the images shown in FIGS. 1 through 7. The process or period in which one image transitions to another image forms no part of the claimed design.
